Primary Examiner — Paula Greene

(74) *Attorney, Agent, or Firm* — Harness, Dickey & Pierce, PLC.

(57) **CLAIM**

The ornamental design for wireless headphones, as shown and described.

DESCRIPTION

FIG. 1 is a rear elevation view of the left ear earphone of the present invention;

FIG. 2 is a front elevation view of the left ear earphone;

FIG. 3 is a right-side elevation view of the left ear earphone;

FIG. 4 is a top plan view of the left ear earphone;

FIG. 5 is a bottom plan view of the left ear earphone;

FIG. 6 is a rear right-side perspective view of the left ear earphone;

FIG. 7 is a rear elevation view of the right ear earphone of the present invention;

FIG. 8 is a front elevation view of the right ear earphone;

FIG. 9 is a right-side elevation view of the right ear earphone;

FIG. 10 is a top plan view of the right ear earphone; and,

FIG. 11 is a perspective view of the right and left ear earphones of the present invention.

The broken lines form no part of the claimed design.

1 Claim, 11 Drawing Sheets
